UNITED STATES PATENT OFFICE

THOMAS P. HANNEGAN, OF ST. PAUL, MINNESOTA

CRANK-CASE HEATER

Application filed April 18, 1929. Serial No. 356,157.

The present invention relates to an oil temperature controlling device for a water cooled motor.

An object of the present invention is to mount a water-tight chamber in the crank case of an internal combustion motor to be immersed in the oil therein, said chamber being connected to the water cooling system of said motor.

10 A further object is to control the oil temperature of a water cooled internal combustion motor by a chamber immersed in the oil in the crank case thereof and connected to the water cooling system of said motor, and having electrically energized heating means immersed in the water contained in said chamber.

In order to attain these objects, there is provided, in accordance with one feature of the 20 invention, a water tight container mounted within the crank case of a water cooled internal combustion motor and having a pair of tubes in open communication therewith, said tubes passing through the wall of the crank case and being connected to the water cooling system of said motor so as to pass a continuous stream of water through said container during the operation of said motor. An electrically energized heating element is 30 mounted within the container and is connected to a pair of conductors which are passed through the crank case in a hermetically sealed conduit.

These and other features of the invention 35 will be more fully brought out in the following description and the accompanying drawings, wherein:

Figure 1, is a view in side elevation of a water cooled internal combustion motor with 40 a device embodying the present invention installed therein.

Figure 2, is a view in side elevation of the device, with a portion of the water container broken away to show the method of mounting the electrical heating element therein.

Figure 3, is a plan view of the device shown in Figure 2, with a portion broken away to show the tube containing the electrical heating element mounted in the container.

50 Figure 4, is a sectional plan view of a dif-

ferent type of heating element than that shown in Figure 3; and

Figure 5, is an end view of the device shown in Figure 4, with a portion broken away to show the method of enclosing the heating element. 55

Referring to the drawings in detail, and considering first the type which is shown in Figures 2 and 3, a container 1 is formed of metal to comprise a hermetically sealed chamber to which threaded outlets 2 and 3 are connected to be in open communication with the interior thereof. 60

A third outlet 4 is mounted between the outlets 2 and 3, to the inner end of which is connected the two ends of a tube 5. These outlets 2, 3, and 4 are preferably made of soft copper, so that when mounting the device in a crank case with sloping sides these outlets may be bent downward so as to bring the container down against the bottom of the crank case. A plate 13 is mounted over the three outlets to hold them in position. Within the tube 5 is mounted a resistance element 6 upon which are strung porcelain beads 7 to keep the element from contact with the tube 5 on which it is mounted. No novelty is claimed for the heating element itself or the porcelain beads in connection therewith, since this is a well-known method of mounting a heating 75 element in a tube. The two ends of the heating element 6 are brought out through the outlet 4 and are connected to brass inserts, not shown, which are mounted in a water tight 80 insulating member inserted in the end of the tube 4 to hermetically seal this tube. A plug 8 having a pair of prongs 9 and 10 thereon is adapted to engage with the brass inserts in the tube 4 to form an electrical contact with 85 said inserts. To the prongs 9 and 10 are connected electrical conductors which are conveyed through a suitable casing 11, such as flexible metal tubing, to an outlet box 12, which may be mounted at any desired point in the structure of the automobile, and is here 90 shown as mounted on the instrument panel. 95

In one method of mounting the device, three holes are drilled in the crank case wall to receive the three outlets 2, 3, and 4. Gaskets are then placed over the outlets and nuts 14 100

are threaded onto the outlets and drawn down to force the gaskets into close engagement with the crank case wall to form a water and oil tight seal therewith.

5 Water tubes 15 and 16 are connected to the threaded outlets 2 and 3 as by means of pipe couplings 17 and 18. A drain cock 19 is connected to the coupling 18 to drain the water from the container and connecting tubes. 10 The tube 15 may be connected to the inlet side of the water pump 20 as at 21, while the other tube 16 is preferably connected into the water jacket of the motor A near the upper end thereof. In this manner the hottest water from the top of the water jacket is 15 drawn downwardly through the tube 16 into the container 1 and thence through the tube 15 to the inlet side of the pump 20.

20 A modified form of heating element is shown in Figures 4 and 5. This type of heating element comprises a flat ribbon 22 of resistance material wound about a flat member 23 of electrical and heat resisting material such as mica or porcelain. The two ends of the conductor are carried through an outlet similar to the outlet 4 in Figure 3 and are connected to brass inserts in an insulative member in the same manner as is described for the type shown in Figure 3. The 25 entire heating element shown in Figures 4 and 5 is enclosed in a separate smaller container 24 which fits within the container 1 to leave a space on both sides thereof between the smaller container 24 and the larger water container 1 to permit a free circulation of water about the heating element container.

30 In operating the device, considering that it is installed in a crank case as hereinbefore described and that it is desired to warm the oil in the crank case and the water in the circulating system before starting the automobile, the conductors enclosed in the casing 11 are connected by suitable means to a source of electrical energy such as a house lighting circuit. This energizes the heating element 6 or 22, depending upon the type of heating element which is installed therein, and this in turn heats the water in the container 1. The container being immersed in the oil in the crank case in turn heats said oil, while a slight circulation of water is caused through the tubes 15 and 16, due to the greater head of water in the tube 16.

35 By leaving the current on for a length of time which is determined by the temperature of the oil in the motor and the heating capacity of the heating element so as to bring the oil in the crank case to a desired temperature, the motor may be readily started and the oil immediately begins to flow. When a motor is started in cold weather without first heating the oil, the oil, being in a semi-solid state, is not circulated by the pump, so that extensive damage is often caused to motors by operating them in cold weather due

to the excessive friction caused when no oil circulation is provided.

Even when the element is not energized so as to pre-heat the oil, before starting the motor, the water in the circulating system heats much more rapidly than the oil in the crank case, owing to the fact that the water surrounds the explosion chambers where the heat of combustion is generated. Thus, when started cold, the water in the circulating system is soon heated, and, as this water is circulated through the container 1, this water in turn heats the oil and brings it to a fluid condition much more rapidly than when the present device is not used.

80 In summer when the oil may have a tendency to overheat, the water in the circulating system, being cooler than the oil will act as a cooling medium and thereby prevent excessive overheating of the oil and help it to retain a proper lubricating body.

If desired, instead of drilling three holes in the side of the crank case to receive the three outlets 2, 3, and 4, a single hole large enough to admit the entire container 1 may be drilled in the side of the crank case and a pair of plates, such as the plate 25, shown in Figure 1, may be mounted one within the crank case and one on the outside of the crank case, to grip the crank case wall therebetween. Suitable gaskets may be provided in a well known manner to form a water and oil tight seal between the plate and the crank case.

95 I claim:

1. A device of the character described, comprising a container mounted in the crank case of an internal combustion motor, a pair of water outlets from said container passing through the wall of said crank case, sealing means surrounding said outlets and engaging the crank case wall to form a water and oil tight seal therewith, and a pair of tubes from said outlets connected to the water circulating system of said motor.

100 2. A device of the character described, comprising a container mounted in the crank case of an internal combustion motor, a pair of water outlets from said container passing through the wall of said crank case, sealing means surrounding said outlets and engaging the crank case wall to form a water and oil tight seal therewith, a pair of tubes from said outlets connected to the water circulating system of said motor, an electrical heating element mounted in said container, and means connecting said heating element to a source of electrical energy.

105 3. A device of the character described comprising a water compartment mounted in the crank case of a water cooled internal combustion motor, a pair of water outlets from said compartment and water conduction means connecting said compartment to the cooling system of said motor.

110 4. A device of the character described com-

prising a water tight compartment mounted in the crank case of a water cooled internal combustion motor, a second water tight compartment mounted internally of said first compartment and having an electrical heating element therein, water conducting means connecting said first compartment to the cooling system of said motor, and conductors connected to said electrical heating element and adapted to be connected to a source of electrical energy.

5 In testimony whereof I affix my signature.
